PITTSFIELD SPARK COIL COMPANY, OF PITTSFIELD, MASSACHUSETTS,
A CORPORATION OF MASSACHUSETTS.

SPEED-GOVERNOR FOR DYNAMOS.

No. 858,002.

Specification of Letters Patent.

Patented June 25, 1907.

Application filed January 18, 1904. Serial No. 189,438.

To all whom it may concern:

Be it known that I, EDWARD B. JACOBSON, a citizen of the United States, residing at Pittsfield, in the county of Berkshire, State of Massachusetts, have invented a certain new and useful Improvement in Speed-Governors for Dynamos, of which the following is a specification, reference being had therein to the accompanying drawings.

10 The invention consists in an improved speed-governor arrangement for dynamos, and, generally speaking, consists in the combination, with a dynamo, and driving devices therefor, of an electro-magnet deriving its 15 energy from the current that is generated by the dynamo and controlling the action of the said driving devices to govern the speed of the dynamo. The said driving devices, preferably, though not necessarily in all 20 cases, are frictional driving devices.

The manner of carrying the invention into effect may be varied without necessarily involving a departure from the spirit of the invention.

25 In the accompanying drawings I have illustrated the best mode in which I have thus far contemplated embodying the invention, and I will explain the latter with reference to the illustrated embodiment.

30 In the drawings,—Figure 1 shows in elevation a dynamo and driving devices therefor, and illustrates the said embodiment of the invention. Fig. 2 shows the same partly 35 in section. Fig. 3 is a detail view in plan showing chiefly the means whereby the driven friction-wheel which is connected with the dynamo is pressed into driving engagement with the driving friction-wheel. Figs. 4 and 5 are diagrams showing the 40 electrical connections to which reference is made hereinafter.

Having reference to the drawings,—at 1 is represented the casing of the dynamo. The dynamo itself may be of any approved construction. In Fig. 2, 2, 2, are the field coils thereof, 3, 3, the pole-pieces, 4 the armature, and 41 the armature shaft.

45 The preferred arrangement of frictional driving devices for the armature shaft 41 comprises a friction-wheel 5 that is fast upon the same, and a driver 6 in the form of a friction-wheel engaging with the said friction-wheel 5. The driving friction-wheel 6 may be the fly-

wheel of an engine in connection with which the dynamo is used. For the purpose of governing the speed of the dynamo, I make provision for varying the frictional engagement of the members or elements of the frictional driving devices with each other. In a driving arrangement comprising friction-wheels, 60 as in the drawings, this variation may be effected by movement of one element or member of the driving train relative to the other thereof. This relative movement in the present instance is permitted by mounting 65 the dynamo movably, and arranging the same to gravitate or be pressed in a direction to occasion the interengagement of the members or elements of the driving train, and also to be moved in the reverse direction so as 70 thereby to reduce the driving effect or to disengage the driving surfaces from each other. Herein, the dynamo is mounted upon a movable carrier, 7, which is actuated with yielding force tending to hold the friction-wheel 5 of 75 the armature shaft in contact with the driver 6. The post or standard 11 of the casing 1 of the dynamo rests upon the said carrier 7 and is attached thereto by means of bolts 12.

80 The mode and means of supporting the carrier 7 may vary in practice. Preferably, although not necessarily, it is pivotally mounted, as at 71, upon a base 8, which latter in practice is secured to a suitable support, not shown. A spring for actuating the carrier is represented at 9, it being formed with opposite coils which are mounted upon a fixed supporting-rod or spindle 10, the opposite extremities of the spring being engaged with the said rod or spindle as at 100, 100, so 85 that the rod or spindle constitutes a fixed abutment from which the spring reacts. For the purpose of transmitting the force of the spring to the carrier, an intermediate portion or loop 91 of the spring 9 engages with a wing or arm 13, which latter is mounted loosely upon the rod or spindle 10 with capacity to turn around the same. By the tension of the spring, the free extremity of the said wing or arm is pressed upwardly 90 against the underside of the carrier 7. The force which is transmitted through the wing or arm acts with a tendency to move the said carrier and the dynamo which is mounted thereon in a direction to press the wheel 5 95 against the wheel 6. Any suitable provision 100

may be made for enabling the tension of the spring 9 to be adjusted so as to secure the proper degree thereof. This adjustment in the present instance is effected by turning 5 the rod or spindle 10 in the required direction, and to the required extent, in the bearings which are provided therefor in the base 8, the rod or spindle being locked in place after adjustment by means of a sliding collar or 10 sleeve 14 which is mounted upon the rod or spindle and notched or toothed at its inner end to engage with one or more fixed projections 15 extending outward from the base 8, the collar or sleeve being slotted longitudinally as at 141, 141, to engage the radially 15 projecting ends of a pin 142 which is applied to the rod or spindle, whereby the sleeve is permitted to move lengthwise of the rod or spindle but prevented from turning relative 20 thereto. The rod or spindle 10 is shown provided with a cross-pin 101 serving as a handle for convenience in turning the same in making adjustment of the tension of the spring.

25 At 16 is shown a vertical post rising from the base 8 and receiving upon its screw-threaded upper portion a nut 161 adapted to serve as a stop by which the movement of the carrier and dynamo under the influence of 30 the spring 9 may be limited in extent. A check-nut 162 is also applied to the said post in connection with the stop-nut 161. Whenever it is desired for the time being to hold the wheel 5 out of driving relations with the 35 wheel 6, this may be effected by turning down the nuts 161, 162, to a suitable extent.

With the dynamo and its movable carrier I combine an electro-magnet which, as before stated, derives its energy from the current that is generated by the dynamo, and 40 which is connected and combined to act in opposition to the force by which the elements or members of the driving train are placed in driving engagement with each other, so as 45 by controlling the driving engagement of the said elements or members to govern the speed of the dynamo. In the present instance, I place below the dynamo a wound coil 17. The core of this coil has at its upper 50 end an enlargement or flange 171 which is in metallic and magnetic contact with the casing 1. This contact is secured in the present instance by causing the said flange to fit tightly within the opening in the base of the 55 casing which it occupies. The core is secured in place within the casing by means of a pin or pins *a*, Fig. 2, inserted through a hole or holes in the casing 1 and entering the periphery of the said enlargement of flange 171. 60 The upper portion of the length of the coil and its core-piece are contained and inclosed within the post or standard 11 of the case 1. The lower portion of the post or standard 11 is in metallic and magnetic contact with the 65 carrier 7. The lower end of the core consti-

tutes one pole of an electro-magnet, and the carrier 7 constitutes the opposite pole, these two poles being yoked together by means of the post or standard. The carrier 7 is formed with an opening 72 through which the lower 70 end of the coil 17 and its core-piece extend. As will be obvious from Fig. 2, the arrangement forms practically an iron-clad magnet. The base 8 constitutes the armature for the said magnet. In order to enable a larger 75 number of ampere turns to be employed in the coil 17 than otherwise would be possible with a post or standard 11 of the height which is shown in the present drawings, the base or armature 8 is chambered 80 out opposite and to receive the lower ends of the coil 17 and its pole-piece. This enables the core-piece to be made longer and thereby to receive more turns of wire than would be possible if the portion of the base which is 85 immediately below the coil were flush with the remainder of the base. The electro-magnet is contained in circuit with the dynamo. Thus, it may be embraced either in a shunt circuit 177 as indicated in the diagram 90 at Fig 4, or in series with the field and armature as indicated in the diagram at Fig. 5. In Figs. 4 and 5 the commutator of the dynamo is indicated at 412.

In operation, the current that is generated 95 by the rotation of the armature through the action of the driving train will energize the magnet, which latter will act with a tendency to separate the friction-wheels, in opposition to the force by which the said friction-wheels 100 are held in driving engagement with each other. When the speed of the dynamo rises so that the increased intensity of the current becomes sufficient to render the magnet powerful enough to overcome the said force, 105 the pressure of the friction-wheels against each other will be lessened so as to reduce the frictional engagement thereof, or the said wheels will be separated, until, by slowing down of the dynamo, the current from the 110 latter becomes so reduced in intensity as to reduce the energy of the magnet below the tension of the spring 9, whereupon the said spring will be permitted to act to press the friction-wheels together again. In this manner 115 the driving and speed of the dynamo will be governed.

What I claim is:—

1. The combination with a movably-mounted dynamo, and driving devices controlled by the position of the dynamo to regulate the speed of the latter, of an electro-magnet acting to vary the position of the dynamo in accordance with variations in the intensity of the current generated thereby. 120

2. The combination with a dynamo, and a driving-train therefor comprising a friction-wheel connected therewith and a driver-wheel with which the periphery of the said friction-wheel makes driving-contact, of an 125 130

electro-magnet deriving its energy from the current generated by the said dynamo, acting with a tendency to separate the elements of said train, and thereby regulating the speed of rotation of the dynamo.

3. In combination, a driver, a movably-mounted dynamo having a power-receiving or driven wheel connected therewith, and an electro-magnet acting to regulate the speed that is imparted to the dynamo, by varying the position of the dynamo in accordance with variations in the intensity of the current generated thereby.

4. In combination, a movably-mounted dynamo, an electro-magnet movable with the dynamo and deriving its energy from the current generated by the dynamo, a fixed magnet-armature, a rotating driver, and a driven-wheel connected with the dynamo and controlled as to its driving relations with the driver by the position of the dynamo.

5. In combination, a movably-mounted dynamo, a driver, a wheel connected with the said dynamo, means to hold the said wheel and driver yieldingly in engagement with each other, and an electro-magnet deriving its energy from the current generated by the dynamo and serving to control the position of the dynamo, whereby the speed of the dynamo is governed.

6. In combination, a dynamo having a stand, a movable carrier constituting with said stand one pole of an electro-magnet, a wound core applied to the stand and providing the other pole of the said electro-magnet; a relatively-fixed magnet-armature, a driver, and a wheel connected with the dynamo and controlled as to its driving relations with the driver by the position of the dynamo and carrier, whereby the speed of the dynamo is governed.

7. In combination, a dynamo, a carrier for the said dynamo having in connection therewith one pole of an electro-magnet, a wound core constituting the opposite pole of the electro-magnet, the said electro-magnet deriving its energy from the current generated by the dynamo, a base having in connection therewith an armature for the said

electro-magnet, and having the said carrier pivotally connected therewith, a driver, and a driven-wheel connected with the dynamo and controlled as to its driving relations with the driver by the position of the dynamo and carrier, whereby the speed of the dynamo is controlled.

8. In combination, a dynamo, a stand for the said dynamo, a carrier with which said stand is connected, the said carrier constituting or having in connection therewith one pole of an electro-magnet, and having an opening therethrough, a wound core in magnetic connection with the said stand and projecting at one end through the opening in the carrier, a base with which said carrier is movably connected, the said base having in connection therewith a fixed magnet-armature, a driver, and a driven-wheel connected with the dynamo and controlled as to its driving relations with the driver by the position of the dynamo and carrier, whereby the speed of the dynamo is controlled.

9. The combination of a suitable support, an electric generator movably mounted upon said support and provided with a pulley by which it may be driven, means for yielding by urging said generator upon the support in one direction, an electro-magnet deriving its energizing current from said generator, and means arranged within the range of said magnet for moving said generator in opposition to said yielding means.

10. The combination of a suitable support, an electric generator movably mounted thereon and provided with an element by which it may be driven, means for yieldingly urging the generator in one direction upon its support, an electro-magnet deriving its energizing current from the generator, and means affected by the electro-magnet for acting upon the generator in opposition to the aforesaid yielding means.

In testimony whereof I affix my signature in presence of two witnesses.

EDWARD B. JACOBSON.

Correction in Letters Patent No. 858,002.

It is hereby certified that in Letters Patent No. 858,002, granted June 25, 1907, upon the application of Edward B. Jacobson, of Pittsfield, Massachusetts, for an improvement in "Speed-Governors for Dynamos," an error occurs in the printed specification requiring correction, as follows: In line 77, page 3, the words "yielding by" should read *yieldingly*; and that the said Letters Patent should be read with this correction therein that the same may conform to the record of the case in the Patent Office.

Signed and sealed this 30th day of July, A. D., 1907.

[SEAL.]

C. C. BILLINGS,

Acting Commissioner of Patents.
